UNITED STATES PATENT OFFICE.

JACOB E. WEISEL, OF SHELBY, OHIO.

STOVEPIPE-FASTENER.

1,197,416.

Specification of Letters Patent. Patented Sept. 5, 1916.

Application filed March 4, 1916. Serial No. 82,169.

To all whom it may concern:

Be it known that I, JACOB E. WEISEL, a citizen of the United States, residing at Shelby, in the county of Richland and State 5 of Ohio, have invented new and useful Improvements in Stovepipe-Fasteners, of which the following is a specification.

This invention relates to certain new and useful improvements in devices adapted for 10 firmly securing a stove pipe within a flue thimble, and at the same time limiting the insertion of the stove pipe within the flue thimble.

The primary object of the invention is the 15 provision of a device of the above stated character wherein means are employed for contracting the clamping band automatically and into clamping engagement with the smoke pipe upon the insertion of the 20 pipe within the flue thimble and said means at the same time controlling the inward movement of the pipe within said flue thimble whereby a perfect draft will be obtained at all times.

25 With the above and other objects in view, the invention consists in the novel features, details of construction and combination of parts which will hereinafter be more fully set forth, illustrated in the accompanying 30 drawing and pointed out in the appended claim.

Figure 1 is a view in perspective showing 35 my improvement as applied to a flue thimble; Fig. 2 is a sectional view illustrating the open position of the clamping band; Fig. 3 is a longitudinal section taken 40 through the thimble clearly illustrating the operating means for the band; and Fig. 4 is a vertical section illustrating the band in clamping position.

Referring more particularly to the accompanying drawing, in which like characters of reference denote corresponding parts in the several views, 5 denotes a flue 45 thimble having disposed therein a split annular clamping band 6 preferably constructed of sheet metal and having its marginal edges reinforced by turning the edges of the band upon itself and indicated by 50 the reference character 7. The object of this clamping band is to automatically clamp the stove pipe 8 and firmly hold the same within the thimble 5 and prevent the pipe from working loose or becoming dislodged from the chimney flue, and to this 55 end I pivotally connect the free ends 9 of

the clamping band 6 to L-shaped ends 10 of a pair of L-shaped toggle links 12, by means of pivot pins 11, while the toggle links at their opposite ends overlap one another and 60 are pivotally connected in overlapped relation one to the other by means of the pivot pin 13 to a longitudinally movable operating bar 14. Each of these toggle links are provided with slightly curved guide slots 15 65 adapted to receive the bolts 16, said bolts serving to spread and close the toggle links upon the operation of the bar 14. These bolts are inserted through the flue thimble and are positively retained thereon by means 70 of the nuts 17, said nuts engaging with a wear plate 18 to prevent the nuts from depressing or marring the thimble to any extent upon the tightening action thereof. The said operating bar 14 is operable in a 75 straight longitudinal line within the thimble 5 and is provided on its inner end with an upwardly and forwardly turned hook 19, the purpose of which is to obstruct the insertion of the stove pipe 8 within the flue 80 and be engaged by its inner end, whereupon a further movement of the stove pipe within the thimble will cause an inward movement of the operating bar, which in turn will rock the L-shaped toggle links on their pivot and 85 cause the band to contract circumferentially and clamp the band in contact with the outer circumference of the stove pipe 8. When it is desirable to release the stove 90 pipe from the thimble the same is accomplished by grasping and pulling on the manipulating member 20 loosely connected to the forward end of the operating bar.

From the foregoing description, taken in 95 connection with the accompanying drawing, the advantages of construction and of the method of operation will be readily apparent to those skilled in the art to which the invention relates, and while I have described the principles of operation of the 100 device together with the device which I now consider to be the best embodiment thereof, I desire to have it understood that the device shown is merely illustrative and that such advantages may be made when desired 105 as are within the scope of the claim appended thereto.

I claim:

The combination with a flue thimble, and 110 a split band adapted to clamp a stove pipe within said flue thimble, of means for operating said band, said means comprising a

hook member movable longitudinally within the thimble and adapted for engagement with the inner end of a stove pipe, a pair of slotted members pivotally connected at one end to the hook member and pivotally connected at their opposite ends to the terminals of the band and operable upon movement of the hook member in one direction to cause a clamping action of the band around and with said pipe, and upon movement of the hook member in the opposite

direction to expand the band into contact with the inner side of the thimble, and a bolt passing through the slot of each of said members and fastened to the thimble.

15

In testimony whereof I affix my signature in presence of two witnesses.

JACOB E. WEISEL.

Witnesses:

LAURA A. WEISEL,
C. E. MORRIS.
